UNITED STATES PATENT OFFICE.

FRANCIS JOYNER, OF NEW YORK, N. Y.

AMUSEMENT DEVICE.

Application filed May 27, 1921. Serial No. 472,984.

To all whom it may concern:

Be it known that I, FRANCIS JOYNER, a citizen of the United States, residing at New York, in the county of New York and State of New York, have invented new and useful Improvements in Amusement Devices, of which the following is a specification.

This invention relates to amusement devices.

More particularly the invention relates to devices for the playing of a game which is played in accordance with the well known baseball rules.

The apparatus or device of the present invention includes what might aptly be termed a target which embodies a playing field having therein a "diamond," and a multiplicity of hooks scattered at random in the field. The device also includes flexible rings which are tossed or pitched to be caught by the said hooks if properly thrown or tossed. Thus far there has been described that which forms the essential parts of the device. Such parts have hitherto been used in game-devices but they do not of themselves furnish the necessary means for playing a game after the fashion of a baseball game and in the same scientific manner in which the actual game of baseball is played. The game-devices hitherto produced of this character involve the element of luck only, in playing therewith, whereas the device of the present invention involves skill as well as luck in playing therewith to be a winner for reasons to be presently explained. At or near the hooks which are arranged in the playing field are divers markings or the like which distinguish the hooks in a manner to indicate the advantages to be gained or lost. The markings or the like are of different colors, and are also of different shapes so as to be readily distinguishable. The markings or the like just mentioned constitutes a means which is visually indicative. At each of the hooks there appears legends denoting offensive and defensive acts or plays. The legends constitute a means which is mentally suggestive to the players in playing the game. The device also includes tally-units for keeping the score. It should now be manifest that, the device of the present invention affords means by which a player may guide himself scientifically to win;

without such means the game would be 55 played without plan or reason.

In the drawing accompanying this specification, Figure 1 is a perspective view of the device; Figure 2 shows one of the toss-rings; Figure 3 shows one of the tally-units. 60

It is well known to those familiar with the game of baseball that there are "offensive acts" and "defensive acts." The "offensive or score advancing acts" are those of the "in-side," whereas, the "defensive or score retarding acts" are those of the "out-side." The "offensive" and "defensive" acts which might occur, are almost without limit. In connection with the present game-device, legends denoting the most frequently occurring acts appear, such as the following: 70 Strike out; Fly out; Out stealing; Double play, which are "defensive acts," and Base on balls; Hit by pitched ball; Stolen base; Error; Balk; Sacrifice hit; One base hit; 75 Two base hit; Three base hit; Home run, which are "offensive acts." The device of the present invention includes a board or plaque 10 about twenty one inches long and about sixteen inches wide. The front face of 80 the board 10 has a playing field 11 thereon in simulation of a regulation baseball field and including a "diamond" 12 with the usual base lines, bases, home-plate and pitchers-box. Scattered over the playing field are 85 hooks 13, which, while they appear to be scattered over the playing field at random are nevertheless arranged with an object in view and that is to have them disposed so that a toss-ring 14 shown in Figure 2 cannot 90 be caught by any two hooks. A hook 13 is arranged at first base, at second base, and at third base. Such particular hooks are of course apt to have one of the toss-rings 95 tossed thereon but they serve also to support the tally-units 15, one of which is shown in Figure 3. The tally-units when arranged on the particular hooks indicate "men on base." The tally-units 15 when arranged on the hook 16 indicate the number 100 of "runs" scored in one "inning" by a player, whereas, the tally-units 15 arranged on the hook 17 indicate the number of "men out" in an "inning."

In order that a player may guide himself 105 to ring a hook under which appears a legend denoting an "offensive act" a marking 18 is placed at or near some of the hooks 13.

The markings 18 may be of different shapes but all are of the same color, namely; red in the present instance. The hooks 13 having the red markings 18, however are not the only hooks as is obvious. Other hooks 13 are associated with other markings. At or near such other hooks, each of them, there appears a legend denoting a "defensive act" and a marking 19. The markings 19 may be 10 of different shapes but all are of the same color, namely; yellow in the present instance. It should now be manifest that though a player may guide himself by the markings 18 to make successful plays it is 15 possible that he may also be unsuccessful.

The board 10 is of a size which does not permit legends to be used which are visible at any appreciable distance. It should therefore be readily understood why the employment of the colored markings are very 20 important in a device of this character. As stated hereinbefore, they furnish a means visually indicative for scientific playing.

The legends Error and Balk strictly 25 speaking are "defensive acts" but they have been included with the "offensive acts." When a toss-ring is tossed over the hook associated with the legend Error a tally-unit 15 is hung on the hook at first 30 base. Likewise when a toss-ring is tossed over the hook associated with the legend Balk, a tally-unit is hung over the hook at first base. It is of course to be understood that should first base be occupied the tally-unit 35 so occupying first base is moved to the second base hook. Out stealing has significance only when a "man is on base" and likewise double play has significance only when there are "men on bases."

40 Twelve toss-rings of rubber are employed. One player tosses at a time that is to say one player plays until three men have been put out when the other player takes up the toss-rings. Each player has nine innings 45 just like a real baseball team.

What is claimed is:

1. An amusement device comprising a target, and toss-rings, the said target embodying a playing field in simulation of a 50 baseball field including a "diamond," hooks in the field on which said toss-rings may be caught, means at some of the hooks mentally suggestive of "offensive" or score advancing and "defensive" or score retarding acts 55 or plays, means at some of the hooks visu-

ally indicative to prompt a player in the exercise of skill, tally-rings, and scoring hooks adapted to retain said tally-rings.

2. A game comprising a target and toss-rings, the said target embodying a playing 60 field in simulation of a baseball field including a "diamond," hooks in the field on which said toss-rings may be caught, means at some of the hooks mentally suggestive of "offensive" or score advancing and "defensive" or score retarding acts or plays, 65 distinguishable markings at some of the hooks to prompt a player in the exercise of skill, tally-rings, and scoring hooks attached to the target, the said scoring hooks adapted 70 to retain said tally-rings.

3. A game comprising a target and toss-rings of rubber, the said target embodying a playing field in simulation of a baseball 75 field including a "diamond," hooks in the field on which said toss-rings may be caught, legends at some of the hooks mentally suggestive of "offensive" or score advancing and "defensive" or score retarding acts or 80 plays, markings of different colors at the hooks having the legends thereat to distinguish the hooks having thereat the "offensive" or score advancing legends from the hooks having thereat the "defensive" or score retarding legends, tally-rings, and 85 scoring hooks attached to the target, the said scoring hooks adapted to retain said tally-rings.

4. An amusement device comprising a target, and toss-rings of rubber, the said target 90 embodying a playing field in simulation of a baseball field including a "diamond," hooks in the field on which the toss-rings may be caught, legends at certain of said hooks denoting "offensive" or score advancing acts or plays, legends at certain other hooks denoting "defensive" or score retarding acts or plays, red markings at the hooks associated with the legends denoting "offensive" or score advancing acts or plays, 95 yellow markings at the hooks associated with the legends denoting "defensive" or score retarding acts or plays, tally-rings, and scoring hooks attached to said target, the said scoring hooks adapted to retain said 100 tally-rings.

In testimony whereof I hereby affix my signature.

FRANCIS JOYNER.
